UNITED STATES PATENT OFFICE.

KARL BARNETT, OF MANCHESTER, INDIANA.

WASHING-MACHINE.

SPECIFICATION forming part of Letters Patent No. 594,058, dated November 23, 1897.

Application filed July 9, 1896, Serial No. 598,502. (No model.)

To all whom it may concern:

Be it known that I, KARL BARNETT, a citizen of the United States, residing at Manchester, Dearborn county, Indiana, have invented new and useful Improvements in 5 Washing-Machines, of which the following is a specification.

My invention relates to washing-machines, its object being to produce a compact, efficient, and easily-operated machine for household use, hereinafter described and claimed.

My invention is illustrated in the accompanying drawings, in which—

Figure 1 is a side elevation of my machine complete; Fig. 2, a sectional elevation, and Fig. 3 a sectional elevation in a plane perpendicular to that of Fig. 2.

Referring now to the drawings, A designates an ordinary rectangular supporting frame on which is mounted on axial pivots a 20 an open approximately semicylindrical vessel B. The pivots are preferably revolubly mounted in spur-pinions a' , having a rolling support in horizontal racks a^2 upon the frame 25 A, and the vessel B is provided at one end with a raised handle by which it may be conveniently oscillated upon its spur-pinion bearings. Each side of the vessel B is provided with an arm b^2 , extending radially upward 30 and slotted or recessed from above downwardly.

The vessel B is provided with a closed bottom extending between its sides and formed to the curvature thereof, just within which 35 from side to side is placed a series of parallel bars b .

Within the vessel B is contained a "rubber" C, being a vessel of substantially the same form as the vessel B, but smaller, with 40 a similarly-curved bottom provided at the exterior with a series of parallel bars c . At each side of the rubber C central arms c' extend upward and carry lateral trunnions c^2 , which extend into the slots of the arms b^2 , 45 and thus suspend the rubber C pivotally within the vessel B. An upward-extending arm c^3 , carried by the rubber, is pivotally connected to a rigid support e , carried by the

frame, through the medium of a lever-arm d . The arm c^3 may be formed by extending the 50 arms c' inward and then upward at the center, which is the construction shown.

The operation is indicated in Figs. 1 and 2, showing different positions. The oscillation of the vessel B gives it a fore-and-aft motion 55 by means of the pinions a' , rolling upon the racks a^2 . The rubber C partakes of this motion, as also the added oscillating motion of the arms b^2 . The point of connection of the arm c^3 with the link d remaining constant, 60 the rubber has a motion opposite that of the vessel B, as indicated by Fig. 2, thus rubbing the clothes between the series of cross-braces b and c . The slot in the arms b^2 being extended upwardly, the rubber C can rise or 65 fall as required. The water is caused to flow back and forth through the clothes by the fore-and-aft motion of the vessel B, as also by its oscillation.

I claim as my invention and desire to secure by Letters Patent of the United States—

In a washing-machine, the combination with a suitable frame carrying at each side a rack, of a semicylindrical containing vessel supported in said frame by means of pinions 75 adapted to rest in the racks; bifurcated arms carried by said containing vessel, a rubber adapted to oscillate in said containing vessel and having bearings supported in the bifurcations of said arms, an upward-extending 80 arm carried by the rubber, an upward-extending support carried by the frame, a lever-arm pivotally connecting the upper ends of said arm and support, and means for rocking the said containing vessel on its bearings, 85 whereby to impart, through the connections described, a counter oscillation to the rubber, substantially as described.

In testimony whereof I have hereunto set my hand in the presence of two subscribing 90 witnesses.

KARL BARNETT.
